No. 709,443.

Patented Sept. 16, 1902.

W. H. STEWART, Dec'd.
M. A. HODGE, Administratrix.
HYDROCARBON BURNER.
(Application filed Nov. 20, 1901.)

UNITED STATES PATENT OFFICE.

MARY A. HODGE, OF SAN JOSE, CALIFORNIA, ADMINISTRATRIX OF WASHINGTON H. STEWART, DECEASED, ASSIGNOR OF THREE-FOURTHS TO WILLIS P. HOLMES AND LEONARD M. HODGE, OF SAN JOSE, CALIFORNIA.

HYDROCARBON-BURNER.

SPECIFICATION forming part of Letters Patent No. 709,443, dated September 16, 1902.

Application filed November 20, 1901. Serial No. 82,994. (No model.)

To all whom it may concern:

Be it known that WASHINGTON H. STEWART, deceased, formerly a citizen of the United States, and a resident of San Jose, in the county of Santa Clara and State of California, did during his lifetime invent a new and useful Hydrocarbon-Burner, of which the following is a specification.

This invention relates to hydrocarbon-burners, the object in view being to provide a simple, effective, and reliable burner for the vaporization and burning of all grades of oil from gasolene to the heaviest of crude oils or petroleum. The construction of the burner is such that the oil is thoroughly disintegrated or atomized, vaporized, and mixed with steam preparatory to burning the same, the burner as a whole consisting of a vaporizer embodying an atomizing and mixing chamber in which is placed a deflector or deflecting-block against which the combined oil and steam is projected with sufficient force to thoroughly atomize the oil and mix it with the steam, after which it is carried forward by the force of the steam through a compact maze composed of closely wrapped or laid meshed wire, wire-cloth, or similar material the density of which is governed by the grade of oil in connection with which the burner is used. The said maze operates to thoroughly and completely disintegrate and vaporize the oil, converting it into a gas or vapor which upon arriving at the tip of the burner ignites and is consumed practically without smoke or residue in the form of carbon or soot. In combining the burner with a furnace or other heater the vaporizer is preferably located exteriorly of the furnace or heater, while the tip of the burner is arranged within the same at any advantageous point.

With the above and other objects in view the invention consists in the novel construction, combination, and arrangement of parts hereinafter fully described, illustrated, and claimed.

In the accompanying drawings, Figure 1 is a side elevation of a hydrocarbon-burner constructed in accordance with the present invention. Fig. 2 is a central longitudinal section through the same. Fig. 3 is an enlarged

central longitudinal section through the steam-chamber and adjacent parts. Fig. 4 is a detail perspective view of the hand adjusting device for the oil-inlet or introduction valve.

55

Like reference-numerals designate corresponding parts in all the figures of the drawings.

Referring to the drawings, 1 designates a spherical atomizing and mixing chamber in which is arranged an adjustable and reversible deflector or deflecting-block 2, having one concave side 3 and one convex side 4, either of which may be presented to the incoming steam and oil. The deflector 2 is located directly opposite the steam and oil nozzle 5 and is removably mounted upon one end of an adjusting-stem 6, which is threaded, as shown at 7, and inserted through a threaded opening 8 in a screw-plug 9, fitted into the end of the vaporizing-chamber, hereinafter described, said stem being provided with a handle 10, preferably in the form of a wheel, by means of which the stem may be turned for adjusting the same inward and outward and varying the distance between the deflector 2 and nozzle 5. When adjusted, the stem may be fixedly secured by means of a jam-nut 11.

The atomizing-chamber 1 is provided at one side with a cylindrical extension 12, forming the vaporizing-chamber. Said chamber is practically filled with a compact maze 13, which preferably consists of closely laid or wrapped meshed wire, wire-cloth, or other similar material the density of which is primarily regulated by the nature or quality of the oil in connection with which the burner is to be subsequently used.

The maze encircles the deflector-stem 6, but does not interfere with the longitudinal movement of said stem, said maze being supported at one end by an inwardly-extending annular flange 14 adjacent to the atomizing-chamber and at its other end by an adjustable stop 15 in the form of a tube extending around the stem 6 and having one end threaded into a socket 16 in the plug 9, thus enabling the tubular stop to be adjusted to bring its projecting end to bear properly against the maze 13. The entire

100

vaporizer, together with the nozzle 5 and the valves leading to and controlling said nozzle, as well as the oil-chamber hereinafter described, are inclosed in an outer jacket 17, 5 within which sufficient space is left to place a filling 18 of some suitable non-conducting material, such as asbestos, which will prevent the too rapid loss and radiation of heat.

Beyond the discharge end of the maze 13 a 10 space 19 is left around the adjustable stop 15, and communicating with the lower portion of said space is a waste or condensation chamber 20, preferably in the form of a hollow sphere, said chamber being connected with the vaporizing-chamber by means of a nipple 21 screwed into a pendent extension of the vaporizing-chamber, as clearly shown in Fig. 2. Said waste-chamber 20 is designed to receive and catch any particles of unvaporized oil or other 15 material in starting the burner and before the vaporizer becomes thoroughly effective by reason of low steam-pressure. This prevents the oil from being carried to the tip of the burner, which would tend to clog the tip.

20 The waste oil and other material passing downward to the waste or condensation chamber 20 may be withdrawn by means of a draw-off cock 22 or may be discharged into a pipe 23, which may be led back to the oil-reservoir.

25 The oil introduction or inlet valve 24 is in the form of a hollow cylinder the discharge end of which is contracted in conical form, as shown in Fig. 2, so as to properly seat itself against the valve-seat 25, formed by the conical inner surface of the nozzle 5. Said nozzle 5 is extended to form a cylindrical valve-casing 26, which is exteriorly threaded and screwed into a cylindrical boss 26', forming an extension of the atomizing-chamber 1 and arranged opposite the vaporizing-chamber 12. 30 Connected with the outer end of the valve-chamber 26 is a cylindrical steam-chamber 27, flanged to fit into the valve-chamber and connected therewith by means of a threaded sleeve or coupling 28, suitable packing 29 being interposed between the chambers 26 and 27 to prevent the escape of steam. The outer end of the steam-chamber 27 is enlarged and interiorly threaded to receive a 35 screw-plug 30, which closes that end of the steam-chamber. The plug 30 is provided with a central boss 31, upon which is rotatably mounted a hand-wheel 32, which is connected with the oil-inlet valve 24 in such manner as to enable said valve to be adjusted 40 thereby. In accomplishing this result the central portion of the hand-wheel 32 is provided with slotted spiral wings or cams 33, as shown in Fig. 4, the slots 34 thereof, which 45 are concentric with the axis of movement of the wheel, receiving headed studs 35, which are connected with parallel arms 36, extending outward from the enlarged end of the cylindrical portion of the oil-inlet valve 24, the said portion of the valve being enlarged, 50 as shown at 37, within the steam-chamber, at which point said cylindrical portion of the

valve is provided with steam-ports 38, through which the steam passes from the steam-chamber to the inside of the cylinder and thence to the valve. The arms 36 pass through openings 39 in the plug 30, and also through small screw-plugs 40, inserted in recesses 41 in the plug coincident with the openings 39, suitable packing 42 being introduced behind the plugs 40 to make a steam-tight fit. The boss 31 is exteriorly threaded to receive a dust-guard nut 43, which prevents dust, dirt, and foreign matter from getting access to the fittings, and said nut 43 is backed up by a 8c jam-nut 44, which acts to lock the dust-guard nut 43. In order to facilitate the adjustment of the oil-inlet valve, the hand-wheel 32 is provided with a pointer or indicator 45, which moves over graduations 46, represented on the outer surface of the steam-chamber, as shown in Fig. 1. In this way the supply of oil may be very accurately regulated.

Within the cylindrical portion of the oil-inlet valve is arranged a stem 47, the inner end of which is tapered in conical form and constitutes the steam-supply valve, said valve working against the conical inner surface of the oil-introduction valve 24, as shown in Fig. 2. The outer end of said stem is threaded and screwed into and through the plug 30, so as to admit of the longitudinal adjustment of the stem 47, the stem and valve being operated by means of a handle 48, preferably in the form of a wheel, as shown. At the point where the stem 47 enters the plug 30 there is arranged a packing or stuffing box 49.

50 represents the steam-supply pipe leading into the steam-chamber 27, and 51 indicates the oil-supply pipe which leads into the oil-chamber 52, comprised by the nozzle 5 and cylindrical portion of the oil-inlet valve 24.

The stem 47 is provided with a plurality of radially-extending wings 53 of equal length, 110 which serve to center the stem within the cylindrical portion of the oil-inlet valve 24, while the valve 24 is centered within the oil-chamber by means of one or more inwardly-extending annular flanges 54 within the oil-chamber.

The hand-wheel 32 is provided in its inner face with an annular groove 55, which receives a corresponding annular flange 56 on the adjacent end of the steam-chamber, thus giving the hand-wheel a bearing and seat against the steam-chamber.

57 represents the pipe leading to the burner-tip 58, at which point the gas or vapor is ignited and consumed.

In order to accurately adjust the steam-inlet valve, the stem 47 is graduated near its outer end, as shown in Figs. 1 and 2, the stuffing-box 49 acting as a pointer or indicator in connection with said graduations to visually indicate the extent to which the steam-inlet valve is opened or closed.

In operation the oil admitted through the pipe 51 flows into the oil-chamber 52 under

sufficient pressure to force it through the nozzle 5 into the atomizing-chamber, the quantity of oil being regulated by the adjustment of the valve 24, which is accomplished by means of the hand-wheel 32. The pointer 45 visually indicates the position of the valve and the consequent supply of oil delivered through the discharge-nozzle. At the same time steam is admitted through the pipe 50, passing into the steam-chamber 27 and through the ports 38 to the inside of the valve 24, where it is discharged into the oil-chamber immediately adjacent to the discharge-opening of the nozzle. At this point the oil and steam are mixed, the oil being taken up by the steam and forced with considerable pressure against the deflector. The oil is thus dashed into atoms, which are directed or diverted by the concave or convex surface 20 of the deflector, according to which side is presented toward the nozzle. When the mixed oil and steam strikes against the concave surface of the deflector, the atoms are thrown backward against the inner surface of the spherical atomizing-chamber, which operates in turn to again deflect the atoms, which are then caught up by the inflowing steam and oil and carried with considerable force toward and into the maze. In case the convex side of the deflector is placed toward the nozzle 5 the oil and steam are directed outward radially against the inner surface of the atomizing-chamber and then forced forward into the maze, the latter operation being preferable when certain grades of oil are used. Thus the oil is thoroughly atomized, mixed with steam, and forced by the steam through the maze 13, which completes the process of thoroughly disintegrating the oil and converting the same into a gas or vapor, which passes out of the vaporizing-chamber through the pipe 57 to the tip of the burner, where it is ignited and consumed practically without residue. Any unvaporized oil which finds its way through the maze drops into the waste or condensation chamber 20, from which it may be drawn off or conducted back to the oil tank or reservoir. By means of the draw-off cock 22 steam in case of an emergency may be directed into the oil tank or reservoir.

The chief advantages of the present invention reside in the maze, its construction and arrangement, the mixing-chamber in connection with the adjustable and reversible deflector, the arrangement, construction, and operation of the valves which control the admission of oil and steam to the mixing-chamber, and the location of the waste or residue chamber. A most important advantage is obtained by the construction of the oil-chamber and the relation of the steam-conduit and oil-supply valve thereto, it being apparent, in view of the description and illustration, that the oil just preparatory to its escape from the nozzle 5 is spread out in a thin annular layer and at the same time heated to a high temperature before it is finally discharged

into the mixing-chamber and thrown against the deflector. The feature just referred to greatly facilitates the disintegration and vaporization of the oil. 70

It will of course be understood that the burner as a whole is susceptible of changes in the form, proportion, and minor details of construction, which may accordingly be resorted to without departing from the principle or sacrificing any of the advantages of the invention. 75

Having thus described the invention, what is claimed as new, and desired to be secured by Letters Patent, is—

1. A hydrocarbon-burner comprising consecutively-arranged atomizing and vaporizing chambers, an oil-supply communicating with the atomizing-chamber, an oil-deflector 85 in the atomizing-chamber, a deflector-supporting stem extending within the vaporizing-chamber, and a maze of meshed fabric surrounding the deflector-stem.

2. A hydrocarbon-burner comprising a 90 spheroidal atomizing-chamber, a vaporizing-chamber, a concavo-convex oil-deflector in the atomizing-chamber, a deflector-supporting stem extending into the vaporizing-chamber, and a wire-gauze maze within the vaporizing-chamber and surrounding the deflector-stem. 95

3. A hydrocarbon-burner comprising consecutively-arranged atomizing and vaporizing chambers, a deflector arranged in the atomizing-chamber, a deflector-supporting stem passing through the vaporizing-chamber, and a maze surrounding the deflector-stem within the vaporizing-chamber, the deflector being adapted to intercept the oil on its way toward 105 the maze.

4. A hydrocarbon-burner comprising an atomizing-chamber, a vaporizing-chamber at one side of the atomizing-chamber, steam and oil supply pipes and controlling-valves therefor located at the opposite side of the atomizing-chamber, and an adjustable imperforate deflector located within the atomizing-chamber. 110

5. A hydrocarbon-burner comprising a mixing and atomizing chamber, a vaporizing-chamber arranged at one side of the atomizing-chamber, oil and steam supply pipes arranged at the opposite side of the atomizing-chamber, and a reversible deflector or deflecting-block located within the atomizing-chamber. 115

6. A hydrocarbon-burner comprising a mixing and atomizing chamber, a vaporizing-chamber arranged at one side of the atomizing-chamber, oil and steam supply pipes and controlling-valves therefor arranged at the opposite side of the atomizing-chamber, and an adjustable and reversible concavo-convex deflector located within the atomizing-chamber. 125

7. A hydrocarbon-burner comprising a vaporizing-chamber, an oil-supply leading toward the same, a spheroidal atomizing-chamber in-

terposed between the oil-supply and vaporizing-chamber, and a normally stationary disk-shaped deflector arranged centrally within the atomizing-chamber and adapted to intercept and spread the oil on its way toward the vaporizing-chamber.

8. A hydrocarbon-burner comprising consecutively-arranged atomizing and vaporizing chambers, a deflector adapted to intercept the oil while passing through the atomizing-chamber toward the vaporizing-chamber, a longitudinally-movable deflector-supporting stem extending through the vaporizing-chamber, and a maze composed of meshed fabric surrounding the deflector-stem and filling the vaporizing-chamber.

9. In a hydrocarbon-burner, consecutively-arranged atomizing and vaporizing chambers, a cap removably applied to one end of the vaporizing-chamber, a deflector arranged in the atomizing-chamber, a deflector-adjusting stem passing through the vaporizing-chamber and cap, and a maze encircling the deflector-stem within the vaporizing-chamber and removable together with the stem, deflector and cap.

10. In a hydrocarbon-burner, the combination with a vaporizing-chamber and means for introducing a mixture of steam and oil

thereto, of a maze substantially filling said vaporizing-chamber, and an adjustable stop forming an abutment for one end of the maze.

11. In a hydrocarbon-burner, the combination with a mixing-chamber, of an oil-chamber terminating in a nozzle leading into the mixing-chamber, a tubular oil-supply valve mounted within the oil-chamber, and a rotary hand-wheel having a cam engagement with said oil-supply valve for adjusting the latter, substantially as described.

12. In a hydrocarbon-burner, the combination with a mixing-chamber, of an oil-chamber terminating in a nozzle leading into the mixing-chamber, a tubular oil-supply valve mounted within the oil-chamber, and a rotary hand-wheel provided with an oblique flange which co-operates with the oil-supply valve for adjusting said valve toward and away from its seat, substantially as described.

In testimony whereof I affix my signature in presence of two witnesses.

MARY A. HODGE,
Administratrix of the estate of Washington H. Stewart.
